(57) **CLAIM**

(21) Appl. No.: **29/132,534**

The ornamental design for a mold produced housing for
enclosing the connection between a cable and a connector,
as shown and described.

(22) Filed: **Nov. 10, 2000**

DESCRIPTION

(51) LOC (7) Cl. **13-03**

FIG. 1 is a front elevational view of a mold produced
housing for enclosing the connection between a cable and a connector
showing my new design.

(52) U.S. Cl. **D13/154; D13/147**

FIG. 2 is a rear elevational view thereof.

(58) Field of Search D13/133, 146,

FIG. 3 is a top plan view thereof.

D13/147, 154, 156; 439/358, 372, 362,

FIG. 4 is a bottom plan view thereof.

588, 606-610

FIG. 5 is a right side elevational view thereof; and,

(56) **References Cited**

FIG. 6 is a left side elevational view thereof.

U.S. PATENT DOCUMENTS

The broken lines in FIG. 1 are included for the purpose of
illustrating environmental structure only and form no part of
the claimed design.
